UNITED STATES PATENT OFFICE

OVID D. ROBINSON, OF CORAOPOLIS, PENNSYLVANIA, ASSIGNOR TO REPUBLIC OIL COMPANY, OF PITTSBURGH, PENNSYLVANIA, A CORPORATION OF DELAWARE

DESIGN FOR A GLOBE

Application filed September 21, 1931. Serial No. 41,172. Term of patent 7 years.

To all whom it may concern:

Be it known that I, OVID D. ROBINSON, a citizen of the United States, residing at Coraopolis, in the county of Allegheny and State of Pennsylvania, have invented a new, original, and ornamental Design for a Globe, of which the following is a specification, reference being had to the accompanying drawings, forming a part thereof.

Fig. 1 is an elevational view showing one side of the globe; Fig. 2 a perspective view showing two sides in elevation; and Fig. 3 a top plan view of the globe.

I claim:

The ornamental design for a globe, as shown.

OVID D. ROBINSON.
